Primary Examiner—Prabhakar G. Deshmukh
Attorney, Agent, or Firm—Cushman Darby & Cushman[57] **CLAIM**

The ornamental design for a base board for a package, as shown and described.

DESCRIPTION

FIG. 1 is a perspective view of a base board for a package from the front, right side and bottom;

FIG. 2 is a front elevational view thereof;

FIG. 3 is a rear elevational view thereof;

FIG. 4 is a right side elevational view thereof, the left side being identical thereto; and,

FIG. 5 is a top plan view thereof, the bottom being identical thereto.

The stippling which appears in FIGS. 1 and 2 depicts a graphical pattern on the front surface of the article.
